UNITED STATES PATENT OFFICE.

GABRIEL CASIMIR ROGER, OF BORDEAUX, FRANCE

SHOE-SOLE-SEWING MACHINE.

Application filed April 23, 1923, Serial No. 634,018, and in Belgium May 10, 1922.

The soles of sandals, slippers, and the like are at present sewn or stitched by hand or by means of machines forming the straight chain stitch which loosens or unravels when the thread is drawn upon from the suitable side.

In order to prevent this disadvantage, I have devised the sewing-machine forming the subject-matter of the invention, for obtaining a stitch, which is stopped or locked against unravelling whenever the thread is drawn in any direction, said stitch being obtained without it being necessary to submit the shoe sole to any previous operation.

15 The essential feature of the machine, which comprises a needle and a shuttle, consists in that the whole of these two parts is so arranged as to perform, after every stitch, a rotation of 180° , in order to present themselves in a position which is symmetrical to the position they previously occupied so as to cross the stitches.

This rotation can be effected either always in the same direction or alternately in one direction and then in the other.

25 Another feature consists in a pusher device which, at the required moment, distorts the sole so as to bend the same, in order to allow the needle to enter the sole without entirely passing through the same.

30 A further feature consists in the feeding device for the sole or work, which allows of mechanically directing the same according to its outline, so that the needle will always present itself normally with reference to the work.

The invention also refers to the devices for carrying out this machine and particularly to the drive of the needle, of the pusher 40 and of the thread-feeding device by means of a cam provided with three grooves.

The following specification, made with reference to the accompanying drawing given by way of example, will give an understanding of the way in which the invention can be carried out.

Figure 1 shows schematically in an elevation view the whole of the machine.

Figure 2 is a detail view, on a larger scale, 50 of the mechanism including the needle, the shuttle and the pusher.

Figure 3 is a front view of Figure 2.

Figure 4 is a perspective detail view of the gear train for the drive of the mechanism.

55 Figures 5 and 6 are views showing parts of the machine.

Figure 7 is a view corresponding to Figure 2, certain parts being removed and some others being cut so as to show the device 60 for carrying along or driving the needle and the pusher by means of a slide.

Figure 8 is a detail view showing the slide in plan.

Figures, 9, 10 and 11 are schematic views 65 showing the position of the different parts of the machine as shewn in Figure 1 during the operation of same.

Figures 12, 13 and 14 are schematic views 70 of a modified form of the machine during the operation of same.

Figure 15 shows the cross stitch, a sort of whip stitch, which is obtained with the machine forming the subject matter of this invention; in this figure the drawing in full 75 lines corresponds to the needle thread, for instance and the drawing in dotted lines, the shuttle thread.

The machine forming the subject-matter of this invention comprises the different following parts:

1. The frame,

2. The needle mechanism which is adapted to cause the needle to enter the sole and to remove the same therefrom;

3. The thread-feeding device for the needle;

4. The shuttle mechanism as used for looping the needle thread;

5. The pusher mechanism which is adapted to bend or bow the sole at the required moment so as to allow the needle to enter the same and to come out therefrom without passing entirely through this sole;

6. The drive for the different above mentioned mechanism; and

7. The mechanism for supporting the sole automatically producing the feed thereof according to the curves shewn thereby as sewing is proceeding, as well as the drive for this mechanism;

1.—*The frame.*—The same is constituted by a fixed standard A, see Figure 1, at the upper part of which is maintained and can

revolve in an intermittent manner a frame d , shewn in detail in Figure 7 which, through its extensions d^0 d^2 acts as a support, among others, to the shuttle-box f and to the arm 5 a^1 carrying the curved needle a , which arm is pivoted at a^2 to the extension d^2 . In this frame can freely slide a cam h^1 which is used for supplying the curved needle a with thread. The frame d is driven, as herein- 10 after explained, so as to remain stationary while the needle a is making a stitch (positions of Figures 1 and 9) and so as to revolve about itself of 180° as soon as the sewing is finished (position of Figure 10), 15 the frame then revolving at same time as the cam.

This cam is driven by an independent driving mechanism and its shaft w which rotates in a continuous manner in the frame 20 d , produces, on the one hand, the reciprocating movement of a slide or carriage c which is suitably connected with the needle a and with the pusher k (Figures 2 and 3) and, on the other hand, the continuous driving 25 of a gear wheel g^1 which causes the shuttle f to rotate.

2.—*Needle mechanism.*—The curved needle a is carried by the finger a^1 pivoted at a^2 and provided at its end with a toothed 30 sector or quadrant a^3 gearing with the sector b^2 of an arm b (Figure 3) pivoted at b^1 (Figures 2 and 3) and the end b^3 of which is provided with an oval hole into which enters the pin b^4 connected with the slide c . 35 As shewn in Figure 2, the arm a^1 is guided in its alternative rotary motion by a fixed circular part a^5 provided at the end of the arm d^3 (Figure 7). In Figure 2, the needle a is shewn as being engaged in the shuttle- 40 box after having pierced the sole S , the needle being guided, in its piercing motion, through the part e , shewn in section Figure 6, carried by an arm connected with the standard A .

45 3.—*Thread-feeding mechanism.*—The thread h^0 is brought to the eye a^0 of the needle a , as shewn in Figure 2, in passing round the tension i^2 , i^3 , the fixed pulley h^6 , the movable pulley h^5 and the fixed pulley 50 h^7 . It will be seen that the pulley h^5 is provided at the end of a take-up arm h^8 pivoted at h^4 upon the frame d and provided with a lug or roller h^2 entering the groove h of a cam h^1 ; the shape of the groove is such that, 55 at the required moment, the pulley h^5 is lowered and allows the thread to follow the reciprocating motions of the needle and of the shuttle; the cam h^1 is provided with a boss i against which bears a rod or rubber i^1 producing, in opposition to the action of a return spring i^4 , the operation of the movable jaw i^3 of the tension, so as to grip the thread and to brake its motion in a well known manner.

60 4.—*Shuttle mechanism.*—The shuttle-box

is maintained between the extensions d^0 , d^2 of the frame d with a certain inclination which is that of the axis or pin f^1 f^2 (Figure 2). The shuttle is driven by the pinion g keyed upon its axle and gearing with the 70 wheel g^1 ; the latter rotates in a continuous manner with the pin or axle w to the extension w^1 of which it is keyed, Figure 7; the whole is arranged so that the shuttle turns so as to loop the needle thread, the said 75 shuttle making more than a half-turn in order to loop the needle-thread and this while the needle is returning from its maximum or outmost driving or piercing point to its starting point, that is to say for a 80 quarter of a revolution of the shaft w .

To this purpose, the pinion g has a radius corresponding to half that of pinion g^1 , so that to every half-turn of the pinion g^1 corresponds a full revolution of the pinion g and consequently of the shuttle, which allows the said shuttle to loop the thread which is supplied from the needle a . It will be observed that the wheel g will revolve about itself only when the frame d and its extensions d^0 , d^2 remain stationary and that on the contrary, the said wheel g , and consequently the shaft of the shuttle, will not revolve about itself when the frame d rotates 180° at same time as the cam shaft w , the wheels g and g^1 rotating as a unit.

5.—*Pusher mechanism.*—In order to allow the needle a to enter the sole and to come out therefrom on the same side, without passing entirely through the said sole, it is necessary to bend or bow the sole as shewn in Figure 2. This is the purpose of pusher k . This pusher is constituted by a rod ended by a fork which is shewn in detail view in Figure 5, the arms k^0 and k^{00} of this fork being provided with holes allowing the passage of the needle a . The rod k slides vertically in a guide j^1 carried by the extension d^2 of frame d . Its upper end carries a lug k^1 engaging a groove k^2 , with inclined end, of the slide c so that at the end of the stroke of the slide c , (Figure 9), the pusher is lifted by the inclined part which forms a slope.

6.—*Driving device for the mechanisms and operation.*—The drive of the mechanisms for producing the sewing or stitching which have just been described can be obtained by means of a single member which is the carriage or slide c which slides in a guide d^1 . This carriage or slide is carried along in its reciprocating motion by a crank pin w^2 , shewn in Figure 7, and in horizontal section Figure 8, continuously revolving with the shaft w .

To every half-turn of the shaft w corresponds a rectilinear motion of the slide or carriage c , as long as the frame d remains stationary.

The said slide c , in sliding, produces, on

the one hand, the driving of the needle into the sole or its removal therefrom through an arm b which is thereby caused to rotate about the point b^1 at every reciprocating movement, and, on the other hand, the vertical displacement of the pusher k by means of groove k^2 .

The whole of the mechanism is so arranged that the operation of the machine will take place in three strokes viz:

1st stroke.—Lowering of the pusher and simultaneous driving of the needle into the sole;

15 2nd stroke.—Removal of the needle which has made its stitch and lifting of the pusher so as to release the sole;

20 3rd stroke.—Revolution of the whole of these parts through 180° so that the needle may make a stitch in a reverse direction to the first one.

The whole of these complex motions can be obtained in any suitable manner for instance through a gear train u , v , u^1 , v^1 , shewn in detail view in Figure 4.

25 The two wheels u and u^1 are keyed to the same shaft m which revolves in a continuous manner and is operated through bevel wheels t and t^1 from the shaft m^1 . This shaft m^1 can be driven in any suitable manner for example by means a fly-wheel m^2 , Figure 1.

With the wheel u gears the wheel v which is keyed to the shaft w connected with the cam h^1 .

35 With the wheel u^1 gears the wheel v^1 keyed to the sleeve x connected with the frame d , said sleeve being free to rotate with reference to shaft w .

40 It will be seen that the frame d is carried or driven quite independently of the cam h^1 .

45 Referring to Figure 4, it will be observed that the wheel v carries a number of teeth which is equal to $2/3$ of the number of teeth of wheel u ; in the example which is represented pinion v has 14 teeth and pinion u , 21 teeth. In other words, the ratio of teeth between the pinions v and u is of two to three.

50 Furthermore, the wheel u^1 is smooth on part of its periphery and carries a toothed sector u^2 (comprising 6 teeth for instance). Finally, the pinion v^1 carries two toothed sectors having the same number of teeth as the sector u^2 , that is to say six teeth, one of the teeth v^2 of each sector being so shaped as to allow the free revolution of the smooth portion u^1 .

60 Accordingly, it will be understood that if the shaft m rotates according to a uniform motion, at every full revolution of the shaft m (and consequently at every full revolution of the pinion u and of the wheel u^1), the pinion v and consequently the shaft w (which carries or drives along the slide

or carriage c) will make one and a half turns, while pinion v^1 (carrying along the frame d) will only make half a turn.

Such being the case, if we take for the start of the strokes or motions the moment when the needle a is at the top of its stroke ready to be driven into the sole (Figures 1 and 2 referring to the end of the driving stroke of the needle), the operation will take place according to the three following strokes:

1st stroke.—The pinion v makes a first half-turn and pinion v^1 remains stationary, the slide c moves from the left to the right, when looking at the figures, so as to come to its outmost right position corresponding to the end of the driving of the needle, Figures 1 and 2, the frame d remaining stationary.

2nd stroke.—The pinion v makes its second half-turn and the pinion v^1 remains stationary; the carriage or slide c comes back to its original position corresponding to Figure 9, position in which the needle has come out the sole, the frame d is always stationary.

3rd stroke.—The pinion v makes its third half-turn and the pinion v^1 driven along by the sector u^2 makes also half a turn in carrying or driving along with it the whole of the cam h^1 , of the slide c and of the frame d ; this whole rotates about itself through 180° as a unit, that is to say without any shifting of one of these parts with reference to the other.

At the end of this revolution the machine occupies the position which is shewn in Figure 10 and the cycle begins again.

It is to be noticed that at the starting of the first stroke, that is to say when the needle has not yet entered the sole, the pusher k is lifted by the inclined groove of the slide c and that, before the needle is driven into the sole, the pusher is lowered under the action of said groove in order to finish the bending of the sole s over its lower pusher l , the curved needle a passing through the holes k^0 , k^{00} of the pusher k .

The pusher remains in the lowered position until about the end of the second stroke when it is lifted again. The stitch being made, the feeding of the sole is then automatically effected through any suitable mechanism, such for instance as one of the kind which will be hereinafter described.

7th.—Automatic sole supporting and feeding mechanism.—The mechanism adapted to hold the material that is to say the sole during the working comprises: a pusher l pressing the sole against the part k ; this pusher l being carried by a lever l^1 which can pivot about the point l^2 secured to the frame of the machine.

A rod l^3 which operates the lever l^1 and which is linked, on the one hand, to said

lever l^1 and on the other hand, to a rod l^4 which latter can pivot about the pivot l^5 and is driven, through the medium of a rod l^6 by a roller l^7 rolling over a cam l^8 carried from the shaft m^1 .

Furthermore, the mechanism which causes the material, that is to say the sole, to move forwards during working comprises following parts:

10 Two claws: an upper claw n carried by a rod n^1 connected with a lever n^2 .

15 A lower claw o carried by a rod o^1 hinged to a lever o^2 which can pivot about l^5 and is operated by a rod o^3 , a roller o^4 and a cam o^5 , the latter being carried by the shaft m^1 ; moreover these two claws can pivot, through suitable means, in a substantially horizontal plane;

20 A part n^3 capable of sliding along the rod o^1 forming one part with n^1 and driven by the lever n^2 driven by a rod n^4 a roller n^5 and a cam n^6 carried from the shaft m^1 ;

25 A part p carrying the lever n^2 which can pivot about the point n^7 ;

30 Convenient springs secured to the frame and returning to suitable positions the levers n^2 and o^2 ;

35 A pin p^1 secured to the frame and about which can swing the part p which controls the feeding of the material in the course of working normally to the plane of Figure 1, through the oscillation of the whole of the two claws in this same plane. These oscillations, the amplitude of which is very small, are facilitated by the presence, at suitable points, of links such as o^8 ;

40 A rod p^2 controlling the motion of the part p , said rod p^2 being secured to the part p^3 at right angle with the part p so as to adjust the amplitude of oscillation and being moved by a roller p^4 and a cam p^5 secured to the shaft m^1 ;

45 A rod n^8 carried by the claw n normal to the plane of Figure 1;

50 An arc q the ends of which bear against the said rod n^8 and which is carried by a lever q^1 pivoting about point q^2 ;

55 A spring q^3 returning to a suitable position the lever q^1 driven by the rod p^2 ; one or several links can be provided if necessary;

60 A finger l^5 , common to the parts l^4 and o^2 , which is capable of being lowered to carry along the parts l and o so as to release the work; this result is attained by means of a lever r which can be adjusted at an angle with reference to the finger l^5 in virtue of the groove r^1 in which the finger l can slide and operated by the lever r^2 which can pivot about point r^3 and linked at r^4 with r . The

65 lever r can pivot about the point r^5 connected with the frame; in order to allow the shifting of point r^3 , the latter is carried by a screw connected at r^6 with the frame of the machine, said screw allowing to adjust the height of point r^3 .

The part q , relieving the part n^8 through the spring q^3 , allows the claws to rotate and to cause the sole to move forwards according to such a curve that the needle will always be driven in at right angle to the tangent of the sole curve, while at this moment the part q is not in contact with the part n^8 ; it will come again in contact with the latter when the claws will have caused the work to move forwards.

75

General operation of the machine.

Let us suppose that a stitch has just been made, the sewing or stitching mechanism being then in a position between that of Figures 1 and 9 (position corresponding to the moment when the needle comes out of the sole but is not yet at the end of its stroke), the claws n and o move apart the one from the other, the part p oscillates, thereby bringing the claws n and o a little backwards above and under the sole at a distance corresponding to the space between two successive stitches; the part q releases the said claws which pivot under the action of the spring n^9 attached at n^{10} to the part n^8 until when the front vertical portion of the claw n bears against the periphery of the sole, said claws pivoting under the action of the spring n^9 if the outline of the sole requires it in a substantially horizontal plane; the claws press again against the sole, the part l is lowered and the pusher k rises again (position of Figure 9), the part p oscillates in a reverse direction, thereby causing the sole to advance; the arc q moves nearer and directs the claws in such manner that the needle can stitch the sole normally to the tangent to the curve corresponding to the outline of the sole.

10

This reverse oscillation of the part p takes place while the stitching mechanism rotates through 180° (third stroke as above described and comes to the position shewn in Figure 10, the needle being ready to make a new stitch, the parts l and the pusher k then come near one another and cause the material or the sole to assume the convenient shape.

The needle a is driven into the sole and loops the thread of the shuttle f , as shewn in Figure 11, then comes back rearwardly and the series of operations are again performed as described.

11

Modification in the construction of the machine.

According to a modified form of construction of the machine which is represented in Figures 12, 13 and 14, the mechanism is simplified, the movements of the needle a and of the pusher k being no longer obtained through the slide or carriage c , but merely by means of two suitable grooves which are independent from the cam h .

12

With reference to the movement of the needle, the arm a^1 is connected with a connecting rod b^0 which can only slide vertically and the end b^4 of which carries a lug 5 or roller which enters into the groove H^2 of the cam h^1 .

It will be understood that when said cam h^1 revolves, the groove H^2 , which is of suitable shape, causes the arm a^1 to pivot about 10 point a^2 , as shewn in Figure 12.

Furthermore, the pusher k , which only slides vertically, is operated directly by the groove H^3 of the cam h^1 which is entered by the end k^3 of the pusher k .

15 As in the previous case, the feeding of the thread is insured by the lever h^3 pivoting at h^4 , the lug or roller h^2 of which enters the groove h of the cam h^1 .

20 The operation of the said stitching mechanism thus modified is the same as the one previously described and takes place in three strokes:-

25 1st stroke.—Lowering of the pusher k , then driving of the needle a into the sole, Figure 12.

2nd stroke.—Releasing of the needle from the sole, looping of the shuttle and lifting of the pusher k , Figure 13.

30 3rd stroke.—Revolution through 180° of the whole of the frame d and of the cam h^1 which has for effect to bring the needle into the position shewn in Figure 14, ready for making a new stitch in a reverse direction to that of the stitch which has just been 35 made.

Whatever the mode of construction of the machine may be, it will be observed that the thread does not pass entirely through the sole and that the stitch cannot go off or unthread when drawing upon the thread. Accordingly, this machine is particularly adapted to be used for shoe-making work; but it can of course be used in connection with all sorts of works in which the advantages 40 resulting from its special stitch can be utilized, for example for making carpets, linen or underwear, for stitching bags, and particularly for making embroidery in which the use of this machine allows to obtain a 45 stitch like the so called cross stitch, the part l being conical or tapered and its variable lifting between the arms of the pusher allowing even to obtain a stitch of variable width, according as the distortion or bending im- 50 parted to the sole by said part l is more or less great.

Of course, the invention is in no way limited to the forms of construction and arrangement which have been more specially 55 described, as it includes, on the contrary, every modification and particularly those in which the feeding or carrying along of the material is effected horizontally or vertically, either through claws, or through the needle, or through rollers, and those in which

the shuttle would be a rotary or vibrating one, in which the needle would be constituted by an ordinary needle or one with hook and with loop maker and the like.

Finally, it will be understood that alterations can be made in the devices which have just been described without departing from the principle of the invention.

What I claim is:

1. A sewing machine comprising a needle, means for operating the needle, means for supplying the needle with sewing thread, a shuttle, means adapted to operate the shuttle, means for distorting a sole to allow the needle to enter and leave the same side, 80 and means for causing the needle and the shuttle to simultaneously rotate through 180° after every stitch.

2. A sewing machine, comprising a needle, means for operating the needle, means for supplying the needle with sewing thread, a shuttle, means adapted to operate the shuttle, a pusher for distorting soles to allow the needle to enter and leave on the same side, 95 means for operating the pusher and means for causing the shuttle, the needle and the pusher to rotate through 180° after every stitch.

3. A sewing machine, comprising a needle, a support for maintaining the needle while 95 allowing the same to effect its reciprocating motions, means operating the needle, means for supplying thread to the needle, a shuttle rotatably mounted in said support, means for causing the shuttle to rotate, a pusher 100 distorting a sole to allow the needle to enter and leave on the same side, means operating the pusher to cause the needle, the shuttle and the pusher to rotate through 180° after every stitch.

4. A sewing machine comprising a needle, means for supplying thread to the needle, a support for maintaining the needle while allowing the same to effect its reciprocating 110 motions, means for producing the motions of the needle, a shuttle rotatably mounted in said support, means for rotating the shuttle, a pusher for distorting a sole, to allow the needle to enter and leave on the same side, co-operating means for controlling at the 115 same time the motions of the pusher, of the needle and of the thread supplying device, and means for causing the needle, the shuttle and the pusher to rotate through 180° after every stitch.

5. A sewing machine comprising a needle, a support for maintaining the needle while allowing the same to effect its reciprocating motions, a shuttle rotatably mounted in said support, means for causing the shuttle to rotate, a pusher for distorting the sole to allow the needle to enter and leave on the same side, cam mechanism for simultaneously controlling the motions of the pusher, 125 the needle, and the thread supplying device, 130

and means for causing the needle, the shuttle and the pusher to rotate through 180° after every stitch.

6. A sewing machine comprising a needle, a support for maintaining the needle while allowing the same to effect its reciprocating motions, a lever for feeding thread to the needle, a shuttle rotatably mounted in said support, a cam for controlling at the same time the motions of the pusher, of the needle and of the thread feeding lever, a bevel gear wheel driven by said cam, another bevel gear wheel meshing with the first one in the ratio of one to two and keyed to the shuttle axle, a pusher for distorting the sole so as to allow the needle to enter and leave on the same side, and means for causing the needle, the shuttle and the pusher to revolve through 180° after every stitch.
10. 7. A sewing machine comprising a needle, a support for maintaining the needle while allowing the same to effect its reciprocating motions, a rotatable shuttle mounted in said support, a cam with three grooves for shifting the pusher, for shifting the needle and supplying the same with thread, a bevel gear wheel driven by the cam, another bevel gear wheel meshing with the first one in the ratio of one to two and keyed to the shuttle axis to rotate it, a pusher for distorting the sole of a shoe to allow the needle to enter and leave on the same side, means for causing the cam to rotate in a continuous manner, and means for causing the rotation through 180° of the support for the needle and the shuttle at the angular speed of the cam after every stitch to avoid relative displacement of the cam and of the support during said rotation, and to cause the rotation of the needle, of the shuttle and of the pusher through 180° without any relative displacement.
15. 8. A sewing machine comprising a needle, a support for maintaining the needle while allowing the same to effect its reciprocating motions, a shuttle rotatably mounted in said support, a device for supplying the needle with thread, a cam with three grooves for simultaneously controlling the motions of the needle, of the shuttle and of the device for supplying the needle with thread, a gear wheel keyed to the cam axle, a second gear

wheel meshing with the first one and having a gearing ratio of 3 to 2, and continuously driven, a double toothed sector keyed to the support for the needle and the shuttle, having the same axis as the first gear, another toothed sector keyed to the axle of the second gear and continuously rotating to continuously drive the cam and rotate through 180° the support after every stitch.

9. A sewing machine comprising a needle, means for operating the needle, means for supplying the needle with sewing thread, a shuttle, means to operate the shuttle, means for distorting the sole of a slipper so as to allow the needle to enter and leave on the same side, means for causing the needle and the shuttle to simultaneously rotate through 180° after every stitch, means for causing the work to move forward automatically and for carrying the same in such manner that the needle will always present itself normally to the tangent to the curve corresponding to the outline of the sole.

10. A sewing machine comprising a needle, a support for maintaining the needle while allowing the same to effect its reciprocating motions, a shuttle rotatably mounted in said support, a device for supplying the needle with thread, a cam with three grooves for controlling at the same time the motions of the needle, of the shuttle and of the device for supplying the needle with thread, a gear keyed to the cam axle, a second gear meshing with the first one and having a gearing ratio of 3 to 2 and continuously driven, a double toothed sector keyed to the support for the needle and the shuttle and having the same axis as the first gear, another toothed sector keyed to the axle of the second gear and revolving in a continuous manner to produce the continuous driving of the cam and the revolution through 180° of the support after every stitch, and means for causing the work to move forward automatically and for carrying the same in such manner that the needle will always present itself normally to the tangent to the curve corresponding to the outline of the sole.

In testimony that I claim the foregoing as my invention, I have signed my name hereto.

GABRIEL CASIMIR ROGER.
